(57) **CLAIM**

The ornamental design for a column segment, as shown and described.

DESCRIPTION

FIG. 1 is a perspective view of a column segment of the present invention;

FIG. 2 is a front view of the column segment;

FIG. 3 is a top plan view of the column segment; and,

FIG. 4 is a bottom plan view of the column segment.

A left side view, a right side view, and a back side view have been omitted since they are each identical to the front view.

The broken line illustrations of portions of the bottom shown in FIG. 4 are for illustrative purposes only and form no part of the claimed invention.
